UNITED STATES PATENT OFFICE.

JOHN H. BELL, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,212,733.

Specification of Letters Patent. Patented Jan. 16, 1917.

Application filed May 16, 1916. Serial No. 97,762.

To all whom it may concern:

Be it known that I, JOHN H. BELL, a subject of the King of Great Britain, residing at East Orange, in the county of Essex and State of New Jersey, have invented certain new and useful Improvements in Telegraph Systems, of which the following is a full, clear, concise, and exact description.

This invention relates to telegraph systems, and more particularly to improvements in systems for repeating or relaying telegraphic signals, differentiated by changes of polarity and current strengths from one line circuit section into another line circuit section, or from one line section into a plurality of other line sections, the repeating operations taking place automatically and in a reciprocal manner with respect to a plurality of line sections grouped for service of this character.

The principal object of this invention is to provide a simplified equipment of devices and circuits to afford economy in the matter of apparatus and current consumption, and to insure greater reliability in the operation of a repeating system of the above type.

A further object of this invention is to provide that the repeating equipment of one line section may be typical of the repeating equipment required by each one of a number of other line sections employed therewith in a repeating system, and to dispense with local circuits or equipment common to a plurality of such line sections.

In accordance with this invention, each line section is provided with a group of four line relays, whereby, in response to polarity and strength variable telegraphic signals primarily set up in any one of the line sections, the relay group of the other line sections is thereby disabled while the latter line sections are joined one with another and receive repeated impulses of current from suitable current sources at the repeating station. As repeated, the impulses correspond to the telegraphic signals set up in the primarily active line section.

This invention is illustrated diagrammatically in the accompanying drawing, in which

Figure 1 represents a repeating equipment for two line circuits or sections, and Fig. 2 represents a repeating equipment suitable for three line sections.

55 Referring to the drawing, it will be noted

that five distinctly grouped equipments, comprising four line relays each, are respectively indicated by reference characters A, B, C, D and E, and that five line circuit sections designated 1, 2, 3, 4 and 5 are operatively included with respective ones of these relay groups. It will also be noted in Fig. 1 that the relays and connections in the group A are typical of the relays and connections comprising the group B, and further, that when telegraphic signals are primarily active in the line section 1, the relays in the group A are responsive to disable the relays in the group B, and also to repeat telegraphic signals from the line section 1 into the line section 2. Accordingly, in response to telegraphic signals primarily set up in the line section 2, the relays in group B are active to disable the relays of the group A, and to repeat the telegraphic signals from the line 2 into the line 1. In a like manner, the relays and connections of the group C in Fig. 2 are respectively typical of the relays and connections comprising the groups D and E of the same figure. The relays in group C become active under signaling impulses in the line 3 to disable the relays of the groups D and E and to repeat the telegraphic signals from the line section 3 into the line sections 4 and 5. And conversely, the group of relays D acts for the line 4 to disable the relay groups C and E, and to repeat signals from the line 4 into the lines 3 and 5. And, in turn, the relays in group E act for the line 5 to disable the group equipments C and D, and to repeat signals from the line 5 into the lines 3 and 4.

In more specifically describing the operation of this system, let it be assumed that the line sections 1 and 2 extend to stations (not shown) at which suitable telegraphic equipments for transmitting and receiving messages by well-known methods are provided. And let it be further assumed that the characteristic form of the transmitted and received current impulses may correspond with predetermined periods of positive current, of negative current, of currents having a predetermined strength, of currents comprising an incremented strength in excess of a predetermined value, and of periods of absence or cessation of current, all in a manner well-known in the telegraph art. Now, during the time the transmitting means at the distant station (not shown) is

active, the current impulses thereby set up in the line 1 may be traced therefrom through the contacts 22 of a relay 17 in the group B, thence over a conductor 6 to the 5 group A, there continuing through the winding of a relay 7, the winding of a relay 8, the winding of a relay 9, thence to the earth connection through the winding of a relay 10. The relays 7 and 8 are adapted to respond to either direct current or to 10 alternating currents, and, therefore, may be termed universal current relays. The characteristics of the two relays differ, however, one from the other. The relay 7 is 15 adapted to operate quickly under the influence of current, but to release slowly on cessation of current; the adjustment of this relay is such that it will respond to all signaling currents which may pass through its 20 windings, as the impulses of strong current or the impulses of weak current. The relay 8 is, on the other hand, adapted to respond quickly under current action, and also to release quickly when current ceases there- 25 through. The adjustment of this relay is such, however, that it will not respond to impulses of weak current, but will remain inert until operated by impulses of strong current. The relay 9, as indicated by the conventional 30 polarity sign, only responds to currents of negative character, while the relay 10, as conventionally labeled, only responds to currents of positive character. These polarized relays are each adjusted to respond to currents of all strengths when of the proper respective polarity, and their armatures are biased (by means not shown) to normally maintain the associated contacts open, and to cause these contacts to 35 separate at each cessation of operating current through their windings.

Let it now be assumed that an impulse of weak negative current is present in the line circuit 1, thereby operating the relays 7 and 40 9, while the relays 8 and 10 remain inert. The contacts 12 of the relay 7, now separated, disconnect the serially connected relays 17, 18, 19 and 20, which comprise the group B, while the closing of the contacts 45 13 of the relay 7 connects the line circuit 2 by way of a resistance unit 11 to a bus conductor 14, which is common to the contacting armatures of the polarized relays 9 and 10. Therefore, as the contacts of the 50 55 polarized relay 9 are now closed, the negative side of a grounded current source 15 is connected through the resistance unit 11, over the path just traced to the line circuit 2. If, now, an impulse of positive current 60 is transmitted from the distant station on the line 1, the negative relay 9 restores to 65 separate its contacts, while the positive relay 10 is operated to close its contacts, and thereby connect the positive side of a ground- ed source of current 16 also by way of the

resistance unit 11 to the line circuit 2. The universal current relay, 7 as described, remains operated under both the negative and the positive impulses of current received over the line 1. The effect of an impulse 70 of negative current having the required increased strength, if now received from the line circuit 1, first assists in restoring the positive relay 10, then causes the operation of the marginally adjusted relay 8 and 75 the negative relay 9. The closing of the contacts of the relay 8 establishes a short circuit around the resistance unit 11; therefore the negative battery 15 is connected through the contacts of the relay 9 and the 80 contacts of the relay 8 to the line circuit 2, the relay 7 remaining operated as described. The shunting out of the resistance unit 11 by the contacts of the relay 8 permits the 85 full potential of the battery 15 to reach the line circuit 2, and therein set up a current of a strength corresponding to that of the current received over the line circuit 1 by which the marginal relay 8 was caused to operate. In a similar manner, a strong im- 90 pulse of positive current from the line circuit 1 also operates the relay 8 to again shunt the resistance unit 11, while the relay 10 responds to connect the positive battery 16 in full potential to the line circuit 2. 95 And conversely, current impulses of char- 100 acteristically reduced strength, transmitted through the circuit of the line 1 as first de- scribed, fail to operate the relay 8, thereby permitting the resistance unit 11 to be pres- 105 ent in the common path by which current from either the negative battery 15 or the positive battery 16 reaches the line circuit 2, thus compensating for and reducing the potential of the working current from these 110 repeater batteries. In this manner, changes of current strength in the line circuit 1 are exactly responded to by the repeating system, and translated in corresponding strength into the line circuit 2.

When messages are being transmitted from the station assumed to be present on the line circuit 2, the signaling currents therein present may be traced through the contacts 12 of the relay 7, thence through 115 the serially connected relays 17, 18, 19 and 20, comprising the group B, to the earth connection. For impulses of current of either polarity in the line circuit 2, the relay 17 responds to separate its contacts 22, 120 thereby disconnecting the relays of the group A, while the closing of its contacts 23 connects the common or bus conductor 24 of the polarized relays 19 and 20, by way of a re- 125 sistance unit 21, to the line circuit 1. The manner in which telegraphic signaling im- pulses are translated from the line circuit 2 into the line circuit 1 by means of the relay group B corresponds in every detail with the operations of the relays in the group A 130

in translating signals from the line circuit 1 into the line circuit 2, as already described.

Referring to Fig. 2 of the drawing, let it be assumed that telegraphic signals of the 5 character described are being set up by a transmitter (not shown) on the line circuit 3. The path of such current impulses may be traced from the line conductor 3, through the contacts 52 of a relay 47, a conductor 56, the contacts 42 of a relay 37, a conductor 57, thence through the winding of each one of the four serially connected relays 27, 28, 29 and 30, comprising repeating relay group C, to the earth connection. The universal current relay 27 continues operated under each 15 character of signaling current as already described for the corresponding relays 7 and 17 of Fig. 2. Separation of the contacts 32 of the relay 27 disconnects the relays comprising the group D, and the separation of 20 the contacts 33 of this relay disconnects the relays of the group E, while the closing of the contacts 34 and 35 of this relay joins the line circuits 4 and 5, one with the other, and, 25 by way of a resistance unit 31, also with the bus conductor 36, which is common to the contacting armatures of the polarized relays 29 and 30. In response to negative and 30 positive impulses of current in the line circuit 3, the polarized relays 29 and 30 respectively connect the negative battery 15 or the positive battery 16 with the line circuits 4 and 5. The marginally adjusted universal current relay 28 only responds to 35 currents in excess of a predetermined strength, and its contacts act to short-circuit the resistance unit 31. This combination corresponds with the relay 8 and the compensating resistance unit 11 of the group A, 40 and, in this case, the resistance 31 is calibrated to so compensate the current which will be repeated into the lines 4 and 5 that each one of these lines will receive a current 45 of a strength corresponding to the originating current impulse transmitted through the line 3. A full strength current impulse in the line circuit 3 causes the relay 28 to operate and shunt out the resistance unit 31, thereby permitting current to be repeated at 50 the full potential of the batteries 15 and 16 into the lines 4 and 5.

Signaling current action primarily taking place in the line circuit 4 completes circuit therefrom over the contacts 32 of the relay 55 27, a conductor 46, the contacts 53 of a relay 47, a conductor 58, thence through the serially connected windings of the relays 37, 38, 39 and 40 comprising the repeating group D, to the earth connection. The contacts 42 60 and 43 of the universal current switching relay 37 disconnect the relay groups C and E respectively, while the contacts 44 and 45 of this relay connect the line circuits 3 and 5 through a resistance unit 41 with the commonly connected contacting armatures of

the polarized relays 39 and 40. The marginally adjusted relay 38 and the relays 39 and 40 of this group act in a manner similar to that already described for the relay group C to repeat signaling impulses from the line 70 circuit 4 into the line circuits 3 and 5. Repeated currents from the batteries in group D, after passing the contacts 44 and 45, respectively, of the relay 37, reach the line circuit 3 by way of the contacts 52 of the relay 75 47, and the line circuit 5 by way of the contacts 33 of the relay 27.

Originating signaling current impulses when transmitted over the line circuit 5 may be traced therefrom over the contacts 33 of 80 the relay 27, a conductor 59, the contacts 43 of a relay 37, thence through the windings of the serially connected relays 47, 48, 49 and 50, comprising the relay group E, to the earth connection. The contacts 52 and 53 of 85 the relay 47 disconnect the relay groups C and D, while the contacts 54 and 55 of this relay connect the line circuits 3 and 4 through a resistance unit 51, with the commonly joined contacting armatures of the 90 polarized relays 49 and 50. This equipment of relays, group E, operates in a manner similar to that already described for the repeating operations of the other groups C and D to translate telegraphic signals from 95 the line circuit 5 into the line circuits 3 and 4. Repeated currents from the batteries of this group, after passing the contacts 54 and 55, respectively, of the relay 47, reach the line circuit 3 directly, and the line circuit 4 after traversing the conductor 46 and the contacts 32 of the relay 27.

Although several sources of current have for convenience been shown in the drawing, it will be understood that all correspondingly poled sources of current may be, and preferably are, one and the same source of current.

In this system, the number of line circuits capable of interacting one with another for 110 the reciprocal repeating of telegraphic signals may be extended by merely placing additional contacts on the switching relays indicated as relays 7, 27, etc.

What is claimed is:

1. In a telegraph repeating system, sources of current, a plurality of line sections, a plurality of line relays for each one of said line sections for repeating telegraphic signals respectively into the other 120 ones of said line sections, and a repeating line relay for each line section adapted to remain inert when traversed by signal impulses of strengths less than a predetermined amount and to respond only to currents in excess of the predetermined strength.

2. In a telegraph repeating system, sources of current, a plurality of line sections, a plurality of line relays for each line 125 130

section to repeat telegraphic signals respectively from one line into the other lines, a current strength regulating means for each line section, and a line relay for each line section to control the operativeness of said regulating means.

3. In a telegraph repeating system, sources of current, a plurality of line sections, a plurality of line relays for each one 10 of said lines for respectively repeating telegraphic signals from any one of said lines into the other lines, an additional line relay for each of said line sections inert under current of one strength but operative under currents of another strength, and means 15 controlled by the last mentioned relay to respectively cause the strength of repeated currents to correspond with the strength of the current received through said additional 20 relay.

4. In a telegraph repeating system,

sources of current, a plurality of line relay groups each comprising a universal current slow-release relay, a universal current marginally adjusted relay and a plurality of 25 polarized relays, a line section for each of said relay groups, contacts operated by the switching relay of any group to disable the relays of the other groups and to join the line sections of the disabled groups one with another, contacts operated by the polarized relays for including said sources of current with said joined line circuits, a resistance unit for each relay group included in the path by which current from said sources 30 may reach the joined line circuits, and contacts operated by said marginally adjusted 35 relay for controlling the operativeness of said resistance unit.

In witness whereof I hereunto subscribe 40 my name this 12th day of May, A. D. 1916.

JOHN H. BELL.
